UNITED STATES PATENT OFFICE.

WALTER A. GIBBS, OF CHURCH CREEK, MARYLAND.

TRAP.

1,232,016.

Specification of Letters Patent.

Patented Mar. 9, 1920.

Application filed April 13, 1916. Serial No. 90,855.

To all whom it may concern:

Be it known that I, WALTER A. GIBBS, residing at Church Creek, in the county of Dorchester and State of Maryland, a citizen of the United States, have invented or discovered certain new and useful Improvements in Traps, of which improvements the following is a specification.

The invention described herein relates to certain improvements in traps and has for its object the provision of an auxiliary trap arranged in such relation to the main trap as to grip the portion of an animal caught in the main trap and to be operated by a movement of the main or primary trap or a portion thereof. The invention is hereinafter more fully described and claimed.

In the accompanying drawing forming a part of this specification, Figures 1 and 2 are side elevations and a top plan view respectively, showing combined primary and auxiliary traps, the latter being controlled by the former, the traps being set in Fig. 2; Figs. 3 and 4 are sectional views on planes, indicated respectively by the lines III—III and IV—IV of Fig. 2; Figs. 5 and 6 show a side elevation and a top plan view illustrating a modification of the combination shown in Figs. 1 and 2, the traps being closed in Fig. 5 and open in Fig. 6. Fig. 7 is a sectional elevation on a plane indicated by the line VII—VII, Fig. 6; Fig. 8 is a side elevation showing a modification of the body mechanism, the trap being closed; Fig. 9 is a plan view of the same, the jaws of the primary trap and the jaws of the auxiliary trap being set or locked in open position; Fig. 10 is a view partly in section and partly in elevation of the form shown in Fig. 9; Fig. 11 is a plan view of a further modification of the invention, the trap being shown open or in operative position; Fig. 12 is a sectional view, the primary trap being shown raised from normal operative position for convenience of illustration; Fig. 13 is a sectional detail view, illustrating the trigger mechanism of the form shown in Figs. 11 and 12; and Fig. 14 is a sectional view on the line XIV—XIV, Fig. 13.

In the practice of the invention, two traps are employed, a main or primary trap being arranged, when in operative position, in such relation to the jaws of the auxiliary trap that the jaws of the latter will close

upon an object caught in the primary trap. While the main or primary trap may be of any suitable construction, it will be generally preferred to employ a trap consisting of jaws 1 provided at their ends with pins 2, which are mounted in bearings in lugs 3 at the ends of the base 4. These jaws are adapted to be closed by a suitably arranged spring, such for example as that shown, consisting of a flat piece of spring metal 11, having one end secured to the base intermediate the lugs and its opposite end constructed to engage and shift the jaws 1 to required position. The spring is adapted to be locked in operative position by a latch 12 pivotally connected to the free end of the spring 11, and adapted when the spring is in operative position to be sprung inwardly to a slot 13 in the base so as to bring its free end in position for engagement with a portion of the treadle 14 when the latter is brought to operative position. One end of the treadle 14 is pivotally and slidably mounted on the spring by means of lugs 15 on the end of an angular extension 16 on one end of the spring, the ends of the lugs being bent in under the spring. When the spring will be shifted to operative position and the latch moved to locking position, the treadle is adjusted to cause the end of the latch to enter a hole in the treadle. In the construction of traps heretofore in general use, having a latch engaging one of the jaws, the latch is necessarily carried by an arm arranged at right angles to the base 4, thus preventing any rocking movement of the trap. It will be found, however, that such rocking or lateral movement of the trap is desirable for the reason that it frequently happens that the animal's foot or other part of the body will not bear centrally on the treadle but at or near one edge, so that one jaw will strike the animal in advance of the other, and when the trap is so constructed and supported as to be incapable of a rocking movement, the jaw first striking the animal will push the leg or other part of the body toward the other jaw. This movement frequently throws the leg entirely out of the path of the closing movement of the jaws. But, by permitting a rocking of the trap, the jaws will meet in planes other than vertical and the trap will be shifted rather than the animal, in its closing movement. This capability of rocking

or lateral movement is of a special advantage where primary and secondary traps are employed, as herein described and claimed, for the reason that this rocking movement of the primary trap can be utilized for releasing the secondary trap.

In the construction shown in Figs. 1 to 4 inclusive, the primary trap is so connected to the base 17 of the auxiliary trap as to be capable of being rocked or turned on such base. The auxiliary trap is of the usual or any suitable construction as regards its jaws 18 and closing spring 19. The auxiliary jaws are locked in open position by means of a rod 20 having its inner end connected to the base 4 of the primary trap and its outer end provided with a finger 21, adapted to engage one of the jaws 18 of the auxiliary trap when in open position. As is well known to users of the style of primary trap described herein, the closing movement of the spring causes a jump or movement of the trap and also that the struggle of an animal when caught will cause violent movements. In the use of the trap described herein, the release of the jaws of the secondary trap follows and is due to the closing movement of the spring of the primary trap. As for example, in the construction shown in Figs. 1 to 4 the rod 20 is so connected to the cross bar 22 of the auxiliary trap that the movements of the latter by its closing spring or by an animal gripped in its jaws will shift the finger 21 out of engagement with the jaws of the auxiliary trap.

In lieu of controlling the operation of the auxiliary trap by the movement of the primary trap, due to the struggling of the animal, when gripped by the latter, the release of the jaws of the auxiliary trap may be effected by the movement of a part or member of the primary trap, when sprung by the animal. As shown in Figs. 5, 6 and 7, the rod 20 is mounted on the cross-bar 22 in the manner hereinbefore described and provided with a finger 21 for engaging one of the jaws of the auxiliary trap, but in lieu of connecting the inner end of the rod to the primary trap, it extends into the path of movement of one of the members of the primary trap, as the spring 23, employed for shifting the jaws of the primary trap.

In Figs. 5 to 7 is shown a useful construction in which the pintles 2 of the jaws are mounted in plates 24 pivotally mounted on lugs 25, secured to the base 17 of the auxiliary trap. Thus mounting the jaws 1 on a pivotal support, renders it possible for the jaws to meet in planes other than vertical. When the jaws are carried by swinging supports, as the plates 24, the spring 23 for shifting the jaws 1 has one end secured to one of the plates and the other end is constructed to shift and lock the jaws in closed

position. As the jaws are so mounted as to be capable of rocking on their base, the means heretofore employed or any other suitable means may be adapted for holding the jaws 1 of the primary trap in open or operative position. As for example, in the construction in Figs. 5 to 7, a latch 26 is so pivoted to an upward extension 27 of the cross arm 22, that it may be turned inwardly over one of the jaws 1 in which position its free end will be engaged by a finger 28 on a pivotally mounted treadle 29.

In Figs. 8 to 10 is shown a means, independent of the jaws, for locking the spring of the auxiliary trap in operative position. This lock consists of a strip of metal 30, one end of which is interposed between the projecting pintles 31 of the jaws 18 and the upper arm of the spring 19, the key or strip of metal lying along the upper arm of the spring. By reference to Figs. 9 and 10 it will be seen that the opening or eye in the upper arm of the spring extends such a distance outside of the jaws that the end of the key projecting under the pintles 31 is unsupported, so that if free to move, the key can be tipped out of engagement with the pintles by the upward pressure of the spring. Such tipping of the key is prevented by employing a clip provided with lugs 32 separated a distance equal to the combined thicknesses of the key and the upper arm of the spring. This clip is carried by a rod 33, provided with a shoulder 34, adapted to bear against the edge of the spring when the clip is in operative position. The inner end of the rod is connected by a chain or other flexible means 35, to the primary trap. The portion of the rod intermediate the shoulder 34 and its connection with the primary trap, inclines outwardly when the clip is in operative position, so that a shifting of the primary trap which is movable, independent of the auxiliary trap, will turn the rod on its shoulder as a fulcrum, and shift the clip out of engagement with the key. It will be readily understood that the primary trap may be of any suitable type, such as that shown in Figs. 8, 9 and 10, having a latch 36, adapted to be held above one of the jaws 1 by a finger 37 on the pivotally mounted treadle 38.

In Figs. 11 and 12, the traps are so constructed as to be free to rock on the base 120 of the auxiliary trap, the locking devices and their release devices being arranged in planes substantially parallel with the jaws of the traps when closed. The primary trap is preferably constructed as shown in Figs. 1, 2, 3, and 4, although other constructions, wherein the locking mechanism does not engage the middle portion of a jaw, may be used. The spring 19^a for the auxiliary trap has one end secured to the 125

base 17^a of the latter, at a point adjacent to one of the lugs 36 in which the jaws 18 are pivotally mounted. The opposite end of the spring has an opening through which passes the other lug 36, said opening being of sufficient size to permit of the free movement of the spring to close the trap. A latch 38 has one end loosely connected to the other end of the spring so that it can be sprung inwardly through a slot 39 in the base 17^a when the spring is depressed. When thus swung, the latch will beat at a point intermediate its ends, against one end of the slot 39 as clearly shown in Fig. 12. The inner end of the latch is supported in locking position by a suitable trigger adapted to be shifted by the primary trap. In the construction shown, the end of the latch is provided with a T-head, the ends of the head being adapted to rest upon the opposite sides of a slot formed in the trigger 40. The latter is provided with lugs 41 projecting down through the slot 39 in the base and having their outer edges notched for the reception of the edges of the slot, as shown in Fig. 14. This construction permits of the trigger being shifted to engage the end of the latch and being tripped by the primary trap so as to bring an opening 42 in the trigger in line with the head of the latch and releasing the latch. The trigger is connected preferably by some flexible means with the primary trap, so that a movement of the latter, as the closing of the jaws 1 or the jerking due to the struggle of the animal when caught by the primary trap, although shown entirely above the auxiliary trap, will rest on the spring 19^a of the

auxiliary trap when the combined traps are set.

I claim herein as my invention:

1. A primary trap and an auxiliary trap, each of said traps having pivotally mounted jaws, and a spring for shifting the jaws to closed position, and means for locking the springs of the primary and auxiliary traps under tension, the primary trap being adapted to be inclosed by the jaws of the auxiliary trap, when held in open or operative position, and movable independently of the auxiliary trap, in combination with means operative by an animal for releasing the spring of the primary trap, and means for releasing the spring of the auxiliary trap and rendered operative by movement resulting from the release of the spring of the primary trap.

2. A primary trap and an auxiliary trap, each trap having pivotally mounted jaws and a spring for shifting said jaws to closed position, each trap having independent means for locking its spring under tension, the primary trap being movably connected to the base of the auxiliary trap in combination with means operative by an animal for releasing the lock of the primary trap, and means operative by the spring or jump of the primary trap when its jaws are released for releasing the spring of the auxiliary trap.

In testimony whereof, I have hereunto set my hand.

WALTER A. GIBBS.
